(57) CLAIM

The ornamental design for a dress, as shown and described.

DESCRIPTION

FIG. 1 is a front elevation view of a first embodiment of a dress, shown in a first configuration;

FIG. 2 is a rear elevation view thereof;

FIG. 3 is a left side view thereof;

FIG. 4 is a right side view thereof;

FIG. 5 is a top plan view thereof;

FIG. 6 is a bottom plan view thereof;

FIG. 7 is a front elevation view of the dress of FIG. 1, shown in a second configuration;

FIG. 8 is a rear elevation view thereof;

FIG. 9 is a left side view thereof;

FIG. 10 is a right side view thereof;

FIG. 11 is a front elevation view of a second embodiment of a dress, shown in a first configuration;

FIG. 12 is a rear elevation view thereof;

FIG. 13 is a left side view thereof;

FIG. 14 is a right side view thereof;

FIG. 15 is a top plan view thereof;

FIG. 16 is a bottom plan view thereof;

FIG. 17 is a front elevation view of the dress of FIG. 11, shown in a second configuration;

FIG. 18 is a rear elevation view;

FIG. 19 is a left side view thereof; and,

FIG. 20 is a right side view thereof.

The evenly broken lines (dash-dot lines) shown in the Figures are only for illustrative purposes to show visible environmental structure and form no part of the claimed invention.

The boundary lines (as opposed to the evenly broken lines) shown in various ones of the Figures in dash-dot-dot form do not exist in reality in the respective article embodying the design and are only for illustrative purposes to show bounds of the claimed design. It is understood that the claimed
